DESIGN FOR AN INDOOR GOLF APPARATUS

David S. Baker, New York, N. Y., assignor to Josiah White, 4th, Atlantic City, N. J.

Application August 3, 1940, Serial No. 94,445

Term of patent 3½ years

To all whom it may concern:

Be it known that I, David S. Baker, a citizen of the United States, residing in New York city, county and State of New York, have invented a new, original, and ornamental Design for an Indoor Golf Apparatus, of which the following is a specification, reference being had to the accompanying drawing, forming part thereof.

The figure is a perspective view of an indoor golf apparatus, showing my new design.

I claim:

The ornamental design for an indoor golf apparatus, as shown.

DAVID S. BAKER.
